US00D638421S

(12) **United States Design Patent**
Tsai

(10) **Patent No.:** US D638,421 S
(45) **Date of Patent:** ** May 24, 2011

(54) **EBOOK READING DEVICE**

(75) Inventor: **Kun-Wei Tsai**, Tu-Cheng (TW)

(73) Assignee: **Cheng UEI Precision Industry Co., Ltd.**, Tu-Cheng, Taipei Hsien (TW)

(**) Term: **14 Years**

(21) Appl. No.: **29/362,791**

(22) Filed: **May 31, 2010**

(51) **LOC (9) Cl.** 14-02

(52) **U.S. Cl.** **D14/346**

(58) **Field of Classification Search** D14/341-346,
D14/371, 374, 138, 439; D18/1, 2, 7; 235/145 A,
235/145 R, 375; 341/22, 23; 345/156, 157,
345/168, 169, 172, 173; 361/679.01-679.03,
